ATTORNEY.

UNITED STATES PATENT OFFICE.

JOHN MÉSZÁROS, OF GLENALUM, WEST VIRGINIA.

RAIL-JOINT FASTENER.

1,387,504.

Specification of Letters Patent. Patented Aug. 16, 1921.

Application filed June 11, 1921. Serial No. 476,684.

To all whom it may concern:

Be it known that I, JOHN MÉSZÁROS, citizen of Hungary, residing at Glenalum, in the county of Mingo and State of West Virginia, have invented certain new and useful Improvements in Rail-Joint Fasteners, of which the following is a specification.

This invention relates to rail joint fasteners for securing together, and to the ties, 10 the ends of track rails.

The invention has for an object to provide a novel form of rail joint fasteners which will act to securely hold the rail ends together, and which includes a simple form of 15 locking means to prevent accidental loosening of the parts.

For further comprehension of the invention, and of the object and advantages thereof, reference will be had to the following description and accompanying drawings, and to the appended claims in which the various novel features of the invention are more particularly set forth.

Figure 1 of the drawings is a plan view 25 showing a portion of a railroad track having the invention applied thereto.

Fig. 2 is an inner side elevation of the fastening plate, with certain exterior parts broken away.

Fig. 3 is a transverse section through a rail equipped with the invention, this view being taken on the line 3—3 of Fig. 4.

Fig. 4 is a side view, with parts broken away of a pair of rail ends and the improved fastening means thereon.

Fig. 5 is a transverse vertical section on the line 5—5 of Fig. 2.

In the drawings the numerals 10 and 11 indicate adjacent track rails, and 12 and 13 40 indicate the ties, the tie 12 being of greater width than the ties 13 and adapted for use at the rail joint.

My improved fastening means comprises a pair of chair members indicated generally 45 at 14 and 15 respectively and shaped on their inner faces to fit snugly upon the tread of the rail and against the web thereof, these chair members overlapping the rail ends, as will be understood, and presenting base 50 flanges 14' and 15' which extend under the rail and vertical fish-plate elements 14^a and 15^a which engage the web of the rail.

Formed on the inner face of the element 14^a is a longitudinal groove 16 which is covered by a face plate 17 secured in place by screws 18. In this groove 16 are mounted

a pair of bars 19 which extend along the groove and are adapted for vertical movement toward and away from one another. These bars are pressed toward one another 60 by pairs of flat springs 20 carried in grooves and fixed at one end to the plate element 14^a, and bearing at their opposite ends against the bars. These bars serve to hold the fastening bolts against displacement. 65

These fastening bolts are indicated at 22 and there may be any suitable number thereof passed through each rail end. The bolts are inserted through suitable registering apertures in the plate element 15^a, the rail 70 webs, and the face plate 17 and extending between the bars 19, the apertures in plate 17 through which the bolts pass being indicated at 17' in Fig. 2. The inner ends of the bolts are notched as at 23, while the 75 bars 19 are of a shape to engage in said notches and so prevent withdrawal of the bolts.

When once inserted in the elements 15^a the bolts 22 are adapted to remain permanently therein, being held against displacement by means of pins such as 24 carried in vertical sockets 25 intersecting the bolts 22 and pressed upwardly into suitable notches in the latter by springs such as 26. 80

To release the bolts 22 from the bars 19, and thus permit of the chair members being separated, the bars are adapted to be moved apart by a key 28 whose head is in the form of a cross 29 and which is inserted in a key-hole slot 30 in the outer face of the member 14 and into the recess 16 and between the bars 19. If desired I may provide a pair of these slots 30, one adjacent each end of the member 14, and employ a separate key 90 in each slot.

The chair members 14, 15 may be secured to the tie 12 by means of spikes 32 of ordinary construction, the tie preferably being of a width equal to the width of these members. 100

Having thus described my invention what I claim as new and desire to protect by Letters Patent of the United States is as follows:

1. A rail fastening device comprising a pair of members adapted to engage the rail ends on opposite sides thereof, bolts passing through one of said members and through the rails, and means confined within the 110 other member for releasably holding said bolts, said means including spring pressed

elements located on opposite sides of the bolts.

2. A rail fastening device comprising a pair of members adapted to engage the rail ends on opposite sides thereof, bolts passing through one of said members and through the rails, and means confined within the other member for releasably holding said bolts, the bolts having notches formed on opposite sides thereof to receive said spring pressed elements.

3. A rail fastening device comprising a pair of members adapted to engage the rail ends on opposite sides thereof, bolts passing through one of said members and through the rails, and means confined within the other member for releasably holding said bolts, and spring pressed bars carried by the first of said members and engaging said

bolts to prevent their withdrawal from the 20 said members.

4. A rail fastening device comprising a pair of members adapted to engage the rail ends on opposite sides thereof, one of said members presenting an interior recess, extending substantially the length thereof, bolts passing through the other member and through the rails and into said recess, the bolts being notched on opposite sides at the points where they are within said recess, 25 a pair of bars extending longitudinally in said recess and adapted to receive the bolts between them, said bars engaging in the notches in the bolts, and springs urging said bars toward one another.

In testimony whereof I have affixed my signature.

JOHN MÉSZÁROS.
